(57) **ABSTRACT**

An active noise control device includes a secondary path filter coefficient updating unit. The secondary path filter coefficient updating unit is configured to update a coefficient of a secondary path filter by using a coefficient of the secondary path filter after previous updating as a previous value, when a phase characteristic of the secondary path filter that sets an initial value as the coefficient and a phase characteristic of the secondary path filter that uses the previous value as the coefficient are not approximate to each other.

ACTIVE NOISE CONTROL DEVICE

CROSS-REFERENCE TO RELATED APPLICATIONS

This application is based upon and claims the benefit of priority from Japanese Patent Application No. 2021-008883 filed on Jan. 22, 2021, the contents of which are incorporated herein by reference.

BACKGROUND OF THE INVENTION

Field of the Invention

The present invention relates to an active noise control device.

Description of the Related Art

JP 2008-239098 A discloses a technique of outputting a canceling sound from a speaker for canceling noise. Such noise is transmitted from a propeller shaft to a vehicle interior. A control signal for outputting the canceling sound from the speaker is generated by performing signal processing with an adaptive filter on a basic signal generated based on a rotational frequency of the propeller shaft. The adaptive filter is updated based on an error signal and the reference signal. The error signal is a signal output from a microphone provided in a vehicle compartment. The reference signal is a signal generated by correcting the basic signal with a correction value.

SUMMARY OF THE INVENTION

In the technique disclosed in JP 2008-239098 A, a transfer characteristic of the canceling sound between the speaker and the microphone is measured in advance, and the measured transfer characteristic is used as the correction value of the basic signal. Therefore, there is concern that the noise cannot be reduced when the transfer characteristic changes.

The present invention has been made to solve the above problem, and an object of the present invention is to provide an active noise control device that is capable of reducing noise even when transfer characteristic changes.

According to one aspect of the present invention, an active noise control device performs active noise control for controlling a speaker, based on an error signal that changes in accordance with a synthetic sound of noise transmitted from a vibration source and a canceling sound output from the speaker to cancel the noise, and includes a basic signal generating unit configured to generate a basic signal corresponding to a control target frequency, a control signal generating unit configured to perform signal processing on the basic signal by a control filter, which is an adaptive notch filter, to generate a control signal that controls the speaker, an estimated noise signal generating unit configured to perform signal processing on the basic signal by a primary path filter, which is an adaptive notch filter, to generate an estimated noise signal, a first estimated cancellation signal generating unit configured to perform signal processing on the control signal by a secondary path filter, which is an adaptive notch filter, to generate a first estimated cancellation signal, a first virtual error signal generating unit configured to generate a first virtual error signal from the error signal, the first estimated cancellation signal, and the estimated noise signal, a secondary path filter coefficient updating unit configured to sequentially and adaptively update a

2

coefficient of the secondary path filter based on the control signal and the first virtual error signal in a manner that a magnitude of the first virtual error signal is minimized, and an initial value table configured to store an initial value of the coefficient of the secondary path filter in table form in association with a frequency, wherein the secondary path filter coefficient updating unit is configured to determine, before updating the coefficient of the secondary path filter, whether or not a phase characteristic of the secondary path filter when the initial value corresponding to the frequency in the initial value table is the coefficient of the secondary path filter and a phase characteristic of the secondary path filter after previous coefficient updating in the secondary path filter coefficient updating unit, are approximate to each other, update, when the phase characteristics are determined to be approximate, the coefficient of the secondary path filter by using the initial value as a previous value, and update, when the phase characteristics are determined not to be approximate, the coefficient of the secondary path filter by using the coefficient of the secondary path filter after the previous coefficient updating as a previous value by the secondary path filter coefficient updating unit.

The active noise control device according to the present invention is capable of reducing noise even when transfer characteristic changes.

The above and other objects, features, and advantages of the present invention will become more apparent from the following description when taken in conjunction with the accompanying drawings, in which a preferred embodiment of the present invention is shown by way of illustrative example.

BRIEF DESCRIPTION OF THE DRAWINGS

FIG. 1 is a diagram illustrating an outline of active noise control executed by an active noise control device;

FIG. 2 is a block diagram of an active noise control device using a method that was proposed by the present inventors and the like;

FIG. 3 is a block diagram of the active noise control device;

FIG. 4 is a diagram illustrating a secondary path filter on a complex plane;

FIG. 5 is a diagram illustrating a secondary path filter on a complex plane;

FIG. 6 is a diagram illustrating a table;

FIG. 7 is a flowchart illustrating a flow of a filter coefficient update process;

FIG. 8 is a graph showing a phase characteristic of a secondary path transfer characteristic and a phase characteristic of a secondary path filter;

FIG. 9 is a graph illustrating sound pressure levels of noise in a vehicle compartment when active noise control is not performed and when active noise control is performed using the secondary path filter; and

FIG. 10 is a graph illustrating sound pressure levels of noise in a vehicle cabin when active noise control is not performed and when active noise control is performed using a secondary path filter.

DESCRIPTION OF THE INVENTION

First Embodiment

FIG. 1 is a diagram illustrating an outline of active noise control executed by an active noise control device 10.

The active noise control device **10** outputs a canceling sound from a speaker **16** provided in a vehicle compartment **14** of a vehicle **12**. The canceling sound cancels a muffled sound of an engine **18** (hereinafter referred to as noise) transmitted to a vehicle occupant due to vibration of the engine **18**, thereby reducing the sound pressure of the noise. In the active noise control device **10**, an error signal e and an engine rotational speed Ne are input. The error signal e is a signal output from a microphone **22** that detects cancellation error noise described later. The engine rotational speed Ne is a detection value detected by an engine rotational speed sensor **24**. The active noise control device **10** generates a control signal $u0$ based on the error signal e and the engine rotational speed Ne . The active noise control device **10** outputs the control signal $u0$ to the speaker **16**, and the speaker **16** outputs the canceling sound based on the control signal $u0$. The cancellation error noise is a synthesized sound of the canceling sound and the noise at a position of the microphone **22**. The microphone **22** is provided on a headrest **20a** of a seat **20** provided in the vehicle compartment **14**. Thus, the microphone **22** is placed near the ears of the vehicle occupant.

Conventional Active Noise Control Device

Conventionally, an active noise control device using an adaptive notch filter (for example, a single-frequency adaptive notch (SAN) filter) having a small amount of computational processing has been proposed.

In the conventional active noise control device, first, a basic signal x having a frequency of noise to be canceled is generated. Hereinafter, the frequency of the noise to be canceled may be referred to as a control target frequency. Next, the active noise control device generates a control signal $u0$ by processing the basic signal x with a control filter W , which is an adaptive notch filter.

The control filter W is updated by an adaptive algorithm (for example, an LMS (Least Mean Square) algorithm) such that the error signal e output from the microphone **22** is minimized. As a result of cancellation of the noise by the canceling sound, the sound pressure of the sound input to the microphone **22** decreases, and then the error signal e also decreases.

A transfer characteristic C is present in a sound transfer path from the speaker **16** to the microphone **22**. The phase of the canceling sound output from the speaker **16** is different from that of the canceling sound input to the microphone **22**. In order to cancel the noise by the canceling sound at the position of the microphone **22**, it is necessary to output the canceling sound from the speaker **16** in consideration of the phase of the canceling sound input to the microphone **22**. The speaker **16** outputs the canceling sound based on the control signal $u0$. The control signal $u0$ is a signal processed by the control filter W . The conventional active noise control device identifies the transfer characteristic C as a filter C' in advance. Then, the conventional active noise control device updates the control filter W using the basic signal x processed by the filter C' . Such control is called a filtered- x type. The transfer characteristic C includes an electronic circuit characteristic of the speaker **16** and an electronic circuit characteristic of the microphone **22**.

The filter C' is a fixed filter identified in advance. Thus, when the transfer characteristic C has been changed, the phase characteristic of the filter C' and the phase characteristic of the transfer characteristic C may be significantly deviated from each other. In this case, there is concern that

when the control filter W is updated, the control filter W may diverge. In addition, the canceling sound output from the speaker **16** may amplify noise, and the canceling sound output from the speaker **16** may become an abnormal sound undesirably.

Therefore, the inventors of the present invention have proposed a method in which the filter C' to follow a change in the transfer characteristic C during active noise control, without the need for identifying the transfer characteristic C in advance. The present invention is a further improvement of the method that was already proposed by the present inventors. An active noise control device **100** using the method already proposed by the present inventors will be schematically described below.

FIG. 2 is a block diagram of the active noise control device **100** using the method proposed by the present inventors. The transfer path of the sound from the engine **18** to the microphone **22** is hereinafter referred to as a primary path. Further, the transfer path of the sound from the speaker **16** to the microphone **22** is hereinafter referred to as a secondary path.

The active noise control device **100** includes a basic signal generating unit **26**, a control signal generating unit **28**, a first estimated cancellation signal generating unit **30**, an estimated noise signal generating unit **32**, a reference signal generating unit **34**, a second estimated cancellation signal generating unit **36**, a primary path filter coefficient updating unit **38**, a secondary path filter coefficient updating unit **40**, and a control filter coefficient updating unit **42**.

The basic signal generating unit **26** generates basic signals xc and xs based on the engine rotational speed Ne . The basic signal generating unit **26** includes a frequency detecting circuit **26a**, a cosine signal generator **26b**, and a sine signal generator **26c**.

The frequency detecting circuit **26a** detects a control target frequency f . The control target frequency f is a vibration frequency of the engine **18** detected based on the engine rotational speed Ne . The cosine signal generator **26b** generates the basic signal xc ($=\cos(2\pi ft)$) which is a cosine signal of the control target frequency f . The sine signal generator **26c** generates the basic signal xs ($=\sin(2\pi ft)$) which is a sine signal of the control target frequency f . Here, t is time.

The control signal generating unit **28** generates control signals $u0$ and $u1$ based on the basic signals xc and xs . The control signal generating unit **28** includes a first control filter **28a**, a second control filter **28b**, a third control filter **28c**, a fourth control filter **28d**, an adder **28e**, and an adder **28f**.

The control signal generating unit **28** performs signal processing on the reference signals xc and xs using the control filter W , which is a SAN filter. The control filter W has a filter $W0$ for the reference signal xc and a filter $W1$ for the reference signal xs . The control filter W is optimized by updating the coefficient $W0$ of the filter $W0$ and the coefficient $W1$ of the filter $W1$ in the control filter coefficient updating unit **42** described later.

The first control filter **28a** has the filter coefficient $W0$. The second control filter **28b** has the filter coefficient $W1$. The third control filter **28c** has a filter coefficient $-W0$. The fourth control filter **28d** has a filter coefficient $W1$.

The basic signal xc processed by the first control filter **28a** and the basic signal xs processed by the second control filter **28b** are added by the adder **28e** to generate the control signal $u0$. The basic signal xs processed by the third control filter **28c** and the basic signal xc processed by the fourth control filter **28d** are added by the adder **28f** to generate the control signal $u1$.

The control signal u_0 is converted into an analog signal by a digital-to-analog converter **17** and output to the speaker **16**. The speaker **16** outputs a canceling sound based on the control signal u_0 .

The first estimated cancellation signal generating unit **30** generates first estimated cancellation signal $y1^\wedge$ based on the control signals u_0 and u_1 . The first estimated cancellation signal generating unit **30** includes a first secondary path filter **30a**, a second secondary path filter **30b**, and an adder **30c**.

The first estimated cancellation signal generating unit **30** performs signal processing on the control signals u_0 and u_1 using the secondary path filter $C^\wedge$, which is a SAN filter. The coefficients ($C0^\wedge + iC1^\wedge$) of the secondary path filter $C^\wedge$ are updated by the secondary path filter coefficient updating unit **40** to be described later, whereby the secondary path transfer characteristic C is identified as the secondary path filter $C^\wedge$.

The filter coefficient of the first secondary path filter **30a** is a real part $C0^\wedge$ of the coefficient of the secondary path filter $C^\wedge$. The filter coefficient of the second secondary path filter **30b** is an imaginary part $C1^\wedge$ of the coefficient of the secondary path filter $C^\wedge$. The control signal u_0 processed by the first secondary path filter **30a** and the control signal u_1 processed by the second secondary path filter **30b** are added by the adder **30c** to generate the first estimated cancellation signal $y1^\wedge$. The first estimated cancellation signal $y1^\wedge$ is an estimation signal corresponding to the canceling sound y input to the microphone **22**.

The estimated noise signal generating unit **32** generates an estimated noise signal $d^\wedge$ based on the basic signals xc and xs . The estimated noise signal generating unit **32** includes a first primary path filter **32a**, a second primary path filter **32b**, and an adder **32c**.

The estimated noise signal generating unit **32** performs signal processing on the basic signal xc using a primary path filter $H^\wedge$ that is a SAN filter. The coefficients ($H0^\wedge + iH1^\wedge$) of the primary path filter $H^\wedge$ are updated by the primary path filter coefficient updating unit **38** to be described later, whereby the transfer characteristic H of the primary path is identified as the primary path filter $H^\wedge$. Hereinafter, the transfer characteristic H of the primary path is referred to as a primary path transfer characteristic H .

The filter coefficient of the first primary path filter **32a** is a real part $H0^\wedge$ of the coefficient of the primary path filter $H^\wedge$. The filter coefficient of the second primary path filter **32b** is a $-H1^\wedge$ obtained by inverting the polarity of the imaginary part of the coefficient of the primary path filter $H^\wedge$. The basic signal xc on which signal processing has been performed by the first primary path filter **32a** and the basic signal xs on which signal processing has been performed by the second primary path filter **32b** are added by the adder **32c** to generate an estimated noise signal $d^\wedge$. The estimated noise signal $d^\wedge$ is an estimated signal corresponding to the noise d input to the microphone **22**.

The reference signal generating unit **34** generates reference signals r_0 and r_1 based on the basic signals xc and xs . The reference signal generating unit **34** includes a third secondary path filter **34a**, a fourth secondary path filter **34b**, a fifth secondary path filter **34c**, a sixth secondary path filter **34d**, an adder **34e**, and an adder **34f**.

The reference signal generating unit **34** performs signal processing on the basic signals xc and xs using a secondary path filter $C^\wedge$, which is a SAN filter. The coefficients ($C0^\wedge + iC1^\wedge$) of the secondary path filter $C^\wedge$ are updated by the secondary path filter coefficient updating unit **40** to be described later, whereby the secondary path transfer characteristic C is identified as the secondary path filter $C^\wedge$.

Hereinafter, the transfer characteristic C of the secondary path is referred to as a secondary path transfer characteristic C .

The filter coefficient of the third secondary path filter **34a** is a real part $C0^\wedge$ of the coefficient of the secondary path filter $C^\wedge$. The filter coefficient of the fourth secondary path filter **34b** is $-C1^\wedge$ obtained by inverting the polarity of the imaginary part of the coefficient of the secondary path filter $C^\wedge$. The filter coefficient of the fifth secondary path filter **34c** is a real part $C0^\wedge$ of the coefficient of the secondary path filter $C^\wedge$. The filter coefficient of the sixth secondary path filter **34d** is an imaginary part $C1^\wedge$ of the coefficient of the secondary path filter $C^\wedge$.

The basic signal xc on which signal processing has been performed by the third secondary path filter **34a** and the basic signal xs on which signal processing has been performed by the fourth secondary path filter **34b** are added by the adder **34e** to generate the reference signal r_0 . The basic signal xs on which signal processing has been performed by the fifth secondary path filter **34c** and the basic signal xc on which signal processing has been performed by the sixth secondary path filter **34d** are added by the adder **34f** to generate the reference signal r_1 .

The second estimated cancellation signal generating unit **36** generates a second estimated cancellation signal $y2^\wedge$ based on the reference signals r_0 and r_1 . The second estimated cancellation signal generating unit **36** includes a fifth control filter **36a**, a sixth control filter **36b**, and an adder **36c**.

The second estimated cancellation signal generating unit **36** performs signal processing on the reference signals r_0 and r_1 using the control filter W , which is a SAN filter. The filter coefficient of the fifth control filter **36a** is W_0 . The filter coefficient of the sixth control filter **36b** is W_1 .

The reference signal r_0 on which signal processing has been performed by the fifth control filter **36a** and the reference signal r_1 on which signal processing has been performed by the sixth control filter **36b** are added by the adder **36c** to generate the second estimated cancellation signal $y2^\wedge$. The second estimated cancellation signal $y2^\wedge$ is an estimation signal corresponding to the canceling sound y input to the microphone **22**.

The analog-to-digital converter **44** converts the error signal e output from the microphone **22** from an analog signal to a digital signal.

The error signal e is input to an adder **46**. The polarity of the estimated noise signal $d^\wedge$ generated by the estimated noise signal generating unit **32** is inverted by an inverter **48**. The estimated noise signal $-d^\wedge$ whose polarity is inverted is input to the adder **46**. The polarity of the first estimated cancellation signal $y1^\wedge$ generated by the first estimated cancellation signal generating unit **30** is inverted by an inverter **50**. The first estimated cancellation signal $-y1^\wedge$ whose polarity is inverted is input to the adder **46**. The estimated noise signal $-d^\wedge$ and the first estimated cancellation signals $-y1^\wedge$ are added by the adder **46** to generate a first virtual error signal e_1 . The adder **46** corresponds to a first virtual error signal generating unit of the present invention.

The estimated noise signal $d^\wedge$ generated by the estimated noise signal generating unit **32** is input to an adder **52**. The second estimated cancellation signal $y2^\wedge$ generated by the second estimated cancellation signal generating unit **36** is input to the adder **52**. The estimated noise signal $d^\wedge$ and the second estimated cancellation signal $y2^\wedge$ are added by the adder **52** to generate the second virtual error signal e_2 . The adder **52** corresponds to a second virtual error signal generating unit of the present invention.

The primary path filter coefficient updating unit 38 sequentially and adaptively updates the coefficient of the primary path filter H^* based on the LMS algorithm such that the magnitude of the first virtual error signal $e1$ is minimized. The primary path filter coefficient updating unit 38 includes a first primary path filter coefficient updating unit 38a and a second primary path filter coefficient updating unit 38b.

The first primary path filter coefficient updating unit 38a and the second primary path filter coefficient updating unit 38b update the filter coefficients $H0^*$ and $H1^*$ based on the following expressions. In the expressions, n denotes the time step ($n=0, 1, 2, \dots$) and $\mu0$ and $\mu1$ denote the step size parameters.

$$H0^*_{n+1} = H0^*_n - \mu0 \times e1_n \times x_{c_n}$$

$$H1^*_{n+1} = H1^*_n - \mu1 \times e1_n \times x_{s_n}$$

The primary path transfer characteristic H is identified as the primary path filter H^* by repeatedly updating the filter coefficients $H0^*$ and $H1^*$ by the primary path filter coefficient updating unit 38. In the active noise control device 100 using the SAN filter, the update expression for the coefficient of primary path filter H^* is configured by four arithmetic operations and does not include a convolution operation. Therefore, it is possible to suppress a computation load due to update processing of the filter coefficients $H0^*$ and $H1^*$.

The secondary path filter coefficient updating unit 40 sequentially and adaptively updates the coefficient of the secondary path filter C^* based on the LMS algorithm such that the magnitude of the first virtual error signal $e1$ is minimized. The secondary path filter coefficient updating unit 40 includes a first secondary path filter coefficient updating unit 40a and a second secondary path filter coefficient updating unit 40b.

The first secondary path filter coefficient updating unit 40a and the second secondary path filter coefficient updating unit 40b update the filter coefficients $C0^*$ and $C1^*$ based on the following expressions. In the expressions, $\mu2$ and $\mu3$ indicate step size parameters.

$$C0^*_{n+1} = C0^*_n - \mu2 \times e1_n \times u0_n$$

$$C1^*_{n+1} = C1^*_n - \mu3 \times e1_n \times u1_n$$

The secondary path transfer characteristic C is identified as the secondary path filter C^* by repeatedly updating the filter coefficients $C0^*$ and $C1^*$ by the secondary path filter coefficient updating unit 40. In the active noise control device 100 using the SAN filter, the update expressions for the filter coefficients $C0^*$ and $C1^*$ are configured by four arithmetic operations and do not include a convolution operation. Therefore, it is possible to suppress a computation load due to update processing of filter coefficients $C0^*$ and $C1^*$.

The control filter coefficient updating unit 42 sequentially and adaptively updates the coefficients $W0$ and $W1$ of the control filter W based on the LMS algorithm such that the magnitude of the second virtual error signal $e2$ is minimized. The control filter coefficient updating unit 42 includes a first control filter coefficient updating unit 42a and a second control filter coefficient updating unit 42b.

The first control filter coefficient updating unit 42a and the second control filter coefficient updating unit 42b update the filter coefficients $W0$ and $W1$ based on the following expressions. In the expressions, $\mu4$ and $\mu5$ denote the step size parameters.

$$W0_{n+1} = W0_n - \mu4 \times e2_n \times r0_n$$

$$W1_{n+1} = W1_n - \mu5 \times e2_n \times r1_n$$

The control filter W is optimized by repeatedly updating the filter coefficients $W0$ and $W1$ by the control filter coefficient updating unit 42. In the active noise control device 100 using the SAN filter, the update expressions for the filter coefficients $W0^*$ and $W1^*$ are configured by four arithmetic operations and do not include a convolution operation. Therefore, it is possible to suppress a computation load due to update processing of filter coefficients $W0^*$ and $W1^*$.

Improvements

Improvements made in the present invention will be described, with respect to the active noise control device 100 using the technique that was already proposed by the present inventors.

FIG. 3 is a block diagram of the active noise control device 10 according to the present embodiment. The active noise control device 10 according to the present embodiment includes, as a signal processing unit 54, the active noise control device 100 using a method that was already proposed by the present inventors. The active noise control device 10 further includes an initial value table 56, an update value table 58, a result value table 60, an initial value table operating unit 62, an update value table operating unit 64, a result value table operating unit 66, and an termination state determination unit 68.

The active noise control device 10 includes an operational processing device and a storage unit (not shown). The operational processing device includes, for example, a processor such as a central processing unit (CPU) or a micro-processing unit (MPU), and a memory such as a ROM or a RAM. The storage unit is, for example, a hard disk, a flash memory, or the like. The active noise control device 10 need not necessarily have a storage unit. Data may be transmitted and received by communications between the active noise control device 10 and the storage space on the cloud. The signal processing unit 54, the initial value table operating unit 62, the update value table operating unit 64, the result value table operating unit 66, and the termination state determination unit 68 are realized by the operational processing unit executing a program stored in the storage unit.

The initial value table 56 is a memory area in table form provided in the ROM. Initial values of the filter coefficients $C0^*$ and $C1^*$ of a secondary path filter C^* , which will be described later, are stored in the initial value table 56. The update value table 58 is a memory area in table form provided in the RAM. The update values of the filter coefficients $C0^*$ and $C1^*$ are stored in the update value table 58. The result value table 60 is a memory area in table form provided in the ROM. The result values of the filter coefficients $C0^*$ and $C1^*$ are stored in the result value table 60.

The initial value table operating unit 62 writes initial values in the initial value table 56, or performs other operations. The update value table operating unit 64 writes update values in the update value table 58, or performs other operations. The result value table operating unit 66 writes result values in the result value table 60, or performs other operations.

The termination state determination unit 68 determines a cause for termination of active noise control. There are three causes for the termination of active noise control. The first one is a normal termination due to stopping of the engine 18, the second one is an abnormal termination due to occurrence of an abnormality in the active noise control, and the third one is a divergence termination due to divergence of the active noise control.

The update processing of the filter coefficients $C0^\wedge$ and $C1^\wedge$ by the secondary path filter coefficient updating unit **40** of the present embodiment is partially different from the update processing of the filter coefficients $C0^\wedge$ and $C1^\wedge$ by the secondary path filter coefficient updating unit **40** of the above-described active noise control device **100**.

First, in the present embodiment, the secondary path filter coefficient updating unit **40** performs determination described below, before updating the filter coefficients $C0^\wedge$ and $C1^\wedge$. The secondary path filter coefficient updating unit **40** determines whether or not the phase characteristic of the secondary path filter $C^\wedge$ after the previous coefficient updating and the phase characteristic of the secondary path filter $C^\wedge$ having the update value as the coefficient are approximate to each other. Since this determination is performed before the filter coefficients $C0^\wedge$ and $C1^\wedge$ are updated, the secondary path filter $C^\wedge$ after the previous coefficient updating can be referred to as the current secondary path filter $C^\wedge$. The update value corresponds to the control target frequency f obtained from the current engine rotational speed Ne . This update value is stored in the update value table **58** of FIG. 6 described later. Hereinafter, the secondary path filter $C^\wedge$ after the previous coefficient updating may be referred to as a previous value secondary path filter $C^\wedge$. Further, the secondary path filter $C^\wedge$ having, as a coefficient, an update value corresponding to the control target frequency f obtained from the current engine rotational speed Ne may be referred to as an update value secondary path filter $C^\wedge$.

When the phase difference θ between the phase characteristic of the previous value secondary path filter $C^\wedge$ and the phase characteristic of the update value secondary path filter $C^\wedge$ is less than 15° , the secondary path filter coefficient updating unit **40** determines that the phase characteristics of the two are approximate to each other. When the phase difference θ between the phase characteristic of the previous value secondary path filter $C^\wedge$ and the phase characteristic of the update value secondary path filter $C^\wedge$ is equal to or larger than 15° , the secondary path filter coefficient updating unit **40** determines that the phase characteristics of the two are not approximate to each other.

FIG. 4 shows a secondary path filter $C^\wedge$ on a complex plane. A point P indicates the position of the previous value secondary path filter $C^\wedge$. Points Q and R indicate the positions of the update value secondary path filter $C^\wedge$. The phase difference θ can be obtained based on the following expression.

$$\theta = \cos^{-1} \frac{C0^\wedge_n \cdot C0^\wedge(f)_u + C1^\wedge \cdot C1^\wedge(f)_u}{(\sqrt{C0^\wedge_n^2 + C1^\wedge_n^2}) \cdot (\sqrt{C0^\wedge(f)_u^2 + C1^\wedge(f)_u^2})}$$

In the filter coefficients $C0^\wedge_n$ and $C1^\wedge_n$ of the above expression, the filter coefficients $C0^\wedge$ and $C1^\wedge$ of the previous value secondary path filter $C^\wedge$ are input, respectively. The filter coefficients $C0^\wedge$ and $C1^\wedge$ of the update value secondary path filter $C^\wedge$ are input to $C0^\wedge(f)_u$ and $C1^\wedge(f)_u$ in the above expression, respectively.

For example, when the update value secondary path filter $C^\wedge$ is located at the point Q shown in FIG. 4, the phase difference θ_q between the update value secondary path filter $C^\wedge$ and the previous value secondary path filter $C^\wedge$ is less than 15° . Therefore, the secondary path filter coefficient updating unit **40** determines that the phase characteristic of the previous value secondary path filter $C^\wedge$ and the phase characteristic of the update value secondary path filter $C^\wedge$ are approximate to each other.

For example, when the update value secondary path filter $C^\wedge$ is located at a point R illustrated in FIG. 4, the phase difference θ_r between the update value secondary path filter $C^\wedge$ and the previous value secondary path filter $C^\wedge$ is 15° or more. Therefore, the secondary path filter coefficient updating unit **40** determines that the phase characteristic of the previous value secondary path filter $C^\wedge$ and the phase characteristic of the update value secondary path filter $C^\wedge$ are not approximate to each other.

Whether or not the phase characteristic of the previous value secondary path filter $C^\wedge$ and the phase characteristic of the updated secondary path filter $C^\wedge$ are approximate to each other may be determined as follows.

FIG. 5 is a diagram showing a secondary path filter $C^\wedge$ on a complex plane. As shown in FIG. 5, the complex plane is divided into 12 regions from S1 to S12 at every predetermined angle of 30° .

When the update value secondary path filter $C^\wedge$ and the previous value secondary path filter $C^\wedge$ are located in the same region, the secondary path filter coefficient updating unit **40** determines that the phase characteristics of the update value secondary path filter $C^\wedge$ and the previous value secondary path filter $C^\wedge$ are approximate to each other. When the update value secondary path filter $C^\wedge$ and the previous value secondary path filter $C^\wedge$ are located in different regions, the secondary path filter coefficient updating unit **40** determines that the phase characteristics of the update value secondary path filter $C^\wedge$ and the previous value secondary path filter $C^\wedge$ are not approximate to each other.

For example, when the update value secondary path filter $C^\wedge$ is located at a point Q shown in FIG. 5, the point Q is located in the same region S2 as the point P which is the position of the previous value secondary path filter $C^\wedge$. Therefore, the secondary path filter coefficient updating unit **40** determines that the phase characteristic of the previous value secondary path filter $C^\wedge$ and the phase characteristic of the update value secondary path filter $C^\wedge$ are approximate to each other.

For example, when the update value secondary path filter $C^\wedge$ is located at a point R illustrated in FIG. 5, the point R is located in a region S1 different from the region S2 of the point P which is the position of the previous value secondary path filter $C^\wedge$. Therefore, the secondary path filter coefficient updating unit **40** determines that the phase characteristic of the previous value secondary path filter $C^\wedge$ and the phase characteristic of the update value secondary path filter $C^\wedge$ are not approximate to each other.

When it is determined that the phase characteristic of the previous value secondary path filter $C^\wedge$ and the phase characteristic of the update value secondary path filter $C^\wedge$ are approximate to each other, the secondary path filter coefficient updating unit **40** according to the present embodiment performs the following processing. That is, the first secondary path filter coefficient updating unit **40a** provided in the secondary path filter coefficient updating unit **40** and the second secondary path filter coefficient updating unit **40b** provided in the secondary path filter coefficient updating unit **40** respectively update the filter coefficients $C0^\wedge$ and $C1^\wedge$ based on the following expressions.

$$C0^\wedge(f)_{n+1} = C0^\wedge(f)_u - \mu_2 \times e1_n \times u0_n$$

$$C1^\wedge(f)_{n+1} = C1^\wedge(f)_u - \mu_3 \times e1_n \times u1_n$$

Update values $C0^\wedge(f)_u$ and $C1^\wedge(f)_u$ corresponding to the control target frequency f are input to the first term (hereinafter referred to as a “pre-update value”) of the right side of each of the above expressions. The control target fre-

quency f is a control target frequency f obtained from the engine rotational speed Ne at the time of the current update (time step $n+1$). Among the filter coefficients $C0^\wedge$ and $C1^\wedge$ in which the engine rotational speed Ne at the time of updating is the same as the engine rotational speed Ne at the time of current updating, the filter coefficients $C0^\wedge$ and $C1^\wedge$ having the latest update time point are input to the pre-update values.

When it is determined that the phase characteristic of the previous value secondary path filter $C^\wedge$ and the phase characteristic of the update value secondary path filter $C^\wedge$ are not approximate to each other, the secondary path filter coefficient updating unit **40** according to the present embodiment updates the filter coefficients $C0^\wedge$ and $C1^\wedge$ in the first secondary path filter coefficient updating unit **40a** and the second secondary path filter coefficient updating unit **40b** based on the following expressions.

$$C0^\wedge_{n+1} = C0^\wedge_n - \mu_2 \times e1_n \times u0_n$$

$$C1^\wedge_{n+1} = C1^\wedge_n - \mu_3 \times e1_n \times u1_n$$

The filter coefficients $C0^\wedge_n$ and $C1^\wedge_n$ updated at the previous update (time step n) are input to the pre-update values of the above expressions. In this case, the filter coefficients $C0^\wedge$ and $C1^\wedge$ having the latest update time point among the filter coefficients $C0^\wedge$ and $C1^\wedge$ updated in the past are input to the pre-update values. The engine rotational speed Ne at the time when the filter coefficients $C0^\wedge$ and $C1^\wedge$ input to the pre-update values are updated is different from the engine rotational speed Ne at the time of the current update.

The secondary path filter coefficient updating unit **40** sets the updated filter coefficients $C0^\wedge$ and $C1^\wedge$ as the filter coefficients of the third secondary path filter **34a**, the fourth secondary path filter **34b**, the fifth secondary path filter **34c**, and the sixth secondary path filter **34d** of the reference signal generating unit **34**.

Update of Filter Coefficient of Secondary Path Filter

FIG. 6 is a diagram illustrating the table. As shown in FIG. 6, the initial value table **56** stores initial values $C0^\wedge(f)_i$ and $C1^\wedge(f)_i$ in table form. The initial values $C0^\wedge(f)_i$ and $C1^\wedge(f)_i$ are stored in the initial value table **56** in association with frequencies. As shown in FIG. 6, the update value table **58** stores the update values $C0^\wedge(f)_u$ and $C1^\wedge(f)_u$ in table form. The update values $C0^\wedge(f)_u$ and $C1^\wedge(f)_u$ are stored in the update value table **58** in association with frequencies. As shown in FIG. 6, the result value table **60** stores the result values $C0^\wedge(f)_r$ and $C1^\wedge(f)_r$ in table form. The result values $C0^\wedge(f)_r$ and $C1^\wedge(f)_r$ are associated with frequencies and stored in the result value table **60**.

The initial values $C0^\wedge(f)_i$ and $C1^\wedge(f)_i$ stored in the initial value table **56** are set based on any of the following (i) to (vi).

- (i) A measured value of the secondary path transfer characteristic C at each frequency;
- (ii) A phase characteristic of a measured value of the secondary path transfer characteristic C at each frequency;
- (iii) An estimated value of the secondary path transfer characteristic C complemented on the basis of measured values of the secondary path transfer characteristics C at representative frequencies;
- (iv) A phase characteristic of an estimated value of the secondary path transfer characteristic C complemented based on measured values of the secondary path transfer characteristics C at representative frequencies;

(v) An estimated value of the secondary path transfer characteristic C estimated by the following expressions:

$$C0^\wedge(f) = a(f) \times \cos(-2\pi f T)$$

5

$$C1^\wedge(f) = a(f) \times \sin(-2\pi f T)$$

Here, T is the time until the sound reaches the microphone **20** from the speaker **16**, and a is an amplitude constant; and (vi) A convenient small value (in a case where an initial value is not particularly set for convenience such as efficiency of system setting).

FIG. 7 is a flowchart showing a flow of update processing of the filter coefficients $C0^\wedge$ and $C1^\wedge$. The process of updating the filter coefficients $C0^\wedge$ and $C1^\wedge$ is executed each time active noise control is performed.

In step S1, the update value table operating unit **64** writes the initial values stored in the initial value table **56** into the update value table **58** as update values ((A) of FIG. 6). That is, the update value table operating unit **64** writes the initial values corresponding to each frequency into the update value table **58** as the update value corresponding to each frequency. Thereafter, the process proceeds to step S2.

In step S2, the frequency detecting circuit **26a** provided in the signal processing unit **54** detects the control target frequency f . Thereafter, the process proceeds to step S3.

In step S3, the secondary path filter coefficient updating unit **40** reads update values corresponding to the control target frequency f ((B) of FIG. 6). Thereafter, the process proceeds to step S4.

In step S4, the secondary path filter coefficient updating unit **40** determines whether or not the phase characteristic of the previous value secondary path filter $C^\wedge$ and the phase characteristic of the update value secondary path filter $C^\wedge$ are approximate to each other. When it is determined that the phase characteristic of the previous value secondary path filter $C^\wedge$ and the phase characteristic of the update value secondary path filter $C^\wedge$ are approximate to each other, the process proceeds to step S5. In a case where it is determined that the phase characteristic of the previous value secondary path filter $C^\wedge$ and the phase characteristic of the update value secondary path filter $C^\wedge$ are not approximate to each other, the process proceeds to step S6.

In step S5, the secondary path filter coefficient updating unit **40** updates the filter coefficients $C0^\wedge$ and $C1^\wedge$ by inputting the update values corresponding to the control target frequency f at the time of this updating to the pre-update values of the update expressions. Thereafter, the process proceeds to step S7.

In step S6, the secondary path filter coefficient updating unit **40** updates the filter coefficients $C0^\wedge$ and $C1^\wedge$ by inputting the filter coefficients $C0^\wedge$ and $C1^\wedge$ after the previous updating to the pre-update values of the update expressions. Thereafter, the process proceeds to step S7.

In step S7, the update value table operating unit **64** writes the updated filter coefficients $C0^\wedge$ and $C1^\wedge$ into the update values corresponding to the control target frequency f in the update value table **58** ((C) of FIG. 6). Thereafter, the process proceeds to step S8.

In step S8, the termination state determination unit **68** determines whether or not the active noise control has ended. If the active noise control has not ended, the process returns to step S2, and if the active noise control has ended, the process proceeds to step S9.

In step S9, the termination state determination unit **68** determines whether or not the active noise control has ended normally. If it is determined that the active noise control has ended normally, the process proceeds to step S10. If it is

determined that the active noise control has abnormally ended or ended in divergence, the process proceeds to step S12.

In step S10, the initial value table operating unit 62 determines whether or not rewriting of the initial values of the initial value table 56 is permitted. If rewriting of the initial value table 56 is permitted, the process proceeds to step S11. When rewriting of the initial value table 56 is not permitted, the update processing of the filter coefficients $C0^\wedge$ and $C1^\wedge$ is ended.

In step S11, the initial value table operating unit 62 rewrites the initial values corresponding to the frequency of the initial value table 56 with the update values corresponding to the frequency of the update value table 58 (D) of FIG. 6. Then, the update processing of the filter coefficients $C0^\wedge$ and $C1^\wedge$ is ended.

In step S12, the result value table operating unit 66 writes the update values corresponding to the frequency of the update value table 58 into the result values corresponding to the frequency of the result value table 60 ((E) of FIG. 6). Then, the update processing of the filter coefficients $C0^\wedge$ and $C1^\wedge$ is ended.

The initial value table 56 and the result value table 60 can be copied to a personal computer or the like connected to the vehicle 12. Therefore, when an abnormality or divergence occurs in the active noise control, the cause of the occurrence of the abnormality or divergence in the active noise control can be verified by comparing the update value stored in the initial value table 56 with the result value stored in the result value table 60.

Operational Effects

The secondary path characteristic C differs depending on the frequency of the canceling sound. In order to identify the secondary path characteristic C more accurately, it is necessary to update the filter coefficients $C0^\wedge$ and $C1^\wedge$ of the secondary path filter $C^\wedge$ for each of the frequencies of the canceling sound.

In the present embodiment, the active noise control device 10 is provided with the initial value table 56 and the update value table 58. As a result, the active noise control device 10 can set the initial values of filter coefficients $C0^\wedge$ and $C1^\wedge$ for respective frequencies. In addition, the active noise control device 10 can update filter coefficients $C0^\wedge$ and $C1^\wedge$ for each of frequencies using update values stored in update value table 58. Since the initial value is set for each frequency, the active noise control device 10 can significantly improve the initial silencing performance, particularly after the start of active noise control. Since filter coefficients $C0^\wedge$ and $C1^\wedge$ are updated for respective frequencies, the active noise control device 10 can identify secondary path characteristic C as secondary path filter $C^\wedge$ more accurately. As a result, the active noise control device 10 can improve silencing performance.

However, when the filter coefficients $C0^\wedge$ and $C1^\wedge$ are updated for each of the frequencies, the filter coefficients $C0^\wedge$ and $C1^\wedge$ corresponding to the frequencies corresponding to the engine rotational speed N_e having a low frequency of occurrence are updated a small number of times and learning progresses slowly. For this reason, the secondary path filter $C^\wedge$ may be largely deviated from the secondary path transfer characteristic C. In this case, problems such as a decrease in the silencing performance of the active noise control device 10 and output of abnormal sound from the speaker 16 may occur.

Hereinafter, an increase in sound pressure of noise by active noise control will be described with reference to FIGS. 8 and 9.

FIG. 8 is a graph showing the phase characteristic of the secondary path transfer characteristic C and the phase characteristic of the secondary path filter $C^\wedge$. In FIG. 8, a thick line indicates the phase characteristic of the secondary path transfer characteristic C, and a thin line indicates the phase characteristic of the secondary path filter $C^\wedge$. Here, the phase characteristic of the secondary path filter $C^\wedge$ is set to 0° at all frequencies.

FIG. 9 is a graph showing the sound pressure level of noise in the vehicle compartment 14 when active noise control is not performed, and the sound pressure level of noise in the vehicle compartment 14 when active noise control is performed using the secondary path filter $C^\wedge$ of FIG. 8. In FIG. 9, a thick line indicates a sound pressure level when active noise control is not performed, and a thin line indicates a sound pressure level of noise when active noise control is performed using the secondary path filter $C^\wedge$.

As illustrated in FIG. 8, the phase difference between the phase characteristic of the secondary path filter $C^\wedge$ and the phase characteristic of the actual secondary path transfer characteristic C is 180° at a frequency around 66 [Hz], a frequency around 100 [Hz], and a frequency around 130 [Hz]. A frequency around 66 [Hz] corresponds to an engine rotational speed around 2000 [RPM]. A frequency around 100 [Hz] corresponds to an engine rotational speed around 3000 [RPM]. A frequency around 130 [Hz] corresponds to an engine rotational speed around 3800 [RPM]. As shown in FIG. 9, the sound pressure level of the noise when the active noise control is performed is higher than the sound pressure level of the noise when the active noise control is not performed at the engine rotational speed around 2000 [RPM], the engine rotational speed around 3000 [RPM], and the engine rotational speed around 3800 [RPM].

The engine rotational speed N_e rarely increases or decreases rapidly. Further, as shown in FIG. 8, since the secondary path transfer characteristic C changes continuously with respect to a change in frequency, when the change in frequency is not rapid, the change in phase characteristic is also not rapid. In the secondary path transfer characteristic C, when the frequency changes by 1 [Hz], the phase characteristic does not change by 10° or more.

Therefore, when the learning of the update value of the update value table 58 is not advanced, the phase characteristic of the previous value secondary path filter $C^\wedge$ may be closer to the phase characteristic of the secondary path transfer characteristic C than the phase characteristic of the update value secondary path filter $C^\wedge$.

Therefore, in the active noise control device 10 of the present embodiment, secondary path filter coefficient updating unit 40 determines whether or not the phase characteristic of update value secondary path filter $C^\wedge$ and the phase characteristic of previous value secondary path filter $C^\wedge$ are approximate to each other. Then, when it is determined that the phase characteristic of the update value secondary path filter $C^\wedge$ and the phase characteristic of the previous value secondary path filter $C^\wedge$ are approximate to each other, the secondary path filter coefficient updating unit 40 updates the filter coefficients $C0^\wedge$ and $C1^\wedge$ as follows. That is, the secondary path filter coefficient updating unit 40 updates the filter coefficients $C0^\wedge$ and $C1^\wedge$ by inputting the update values $C0^\wedge(f)_u$ and $C1^\wedge(f)_u$ corresponding to the control target frequency f to the pre-update values of the update expressions. On the other hand, when it is determined that the phase characteristic of the update value secondary path filter

C^* is not approximate to the phase characteristic of the previous value secondary path filter C^* , the secondary path filter coefficient updating unit **40** updates the filter coefficients $C0^*$ and $C1^*$ in the following manner. That is, the secondary path filter coefficient updating unit **40** updates the filter coefficients $C0^*$ and $C1^*$ by inputting the updated filter coefficients $C0^* n$ and $C1^* n$ at the previous time (time step n) to the pre-update values of the update expressions.

FIG. 10 is a graph showing a sound pressure level of noise in the vehicle compartment **14** in a case where the active noise control is not performed and a sound pressure level of noise in the vehicle compartment **14** in a case where the active noise control of the present embodiment is performed. In FIG. 10, a thick line indicates a sound pressure level when active noise control is not performed, and a thin line indicates a sound pressure level of noise when active noise control of the present embodiment is performed.

In the active noise control according to the present embodiment, it is possible to prevent the filter coefficients $C0^*$ and $C1^*$ of the secondary path filter C^* , which have a characteristic greatly deviating from the secondary path transfer characteristic C , from being input to the pre-update values of the update expressions for the filter coefficients $C0^*$ and $C1^*$. As a result, as shown in FIG. 10, in the active noise control of the present embodiment, it is possible to suppress an increase in the sound pressure level of noise compared to a case where the active noise control is not performed.

The active noise control device **10** according to the present embodiment can improve the convergence performance of active noise control. Accordingly, the active noise control device **10** of the present embodiment can improve the initial noise reduction performance after the start of active noise control, and can suppress the generation of abnormal noise in vehicle compartment **14** even in a state where secondary path filter C^* is not converged. Furthermore, the active noise control device **10** of the present embodiment can improve quietness in the vehicle compartment **14** after the secondary path filter C^* has converged.

Further, in the active noise control device **10** of the present embodiment, secondary path filter coefficient updating unit **40** determines that the phase characteristic of previous value secondary path filter C^* and the phase characteristic of update value secondary path filter C^* are approximate to each other when phase difference θ between the phase characteristic of previous value secondary path filter C^* and the phase characteristic of update value secondary path filter C^* is less than 15° . Thus, in the active noise control device **10** of the present embodiment, it can be determined with high accuracy whether or not the phase characteristic of previous-value secondary path filter C^* and the phase characteristic of update value secondary path filter C^* are approximate to each other.

Further, in the active noise control device **10** of the present embodiment, secondary path filter coefficient updating unit **40** determines that the phase characteristic of previous value secondary path filter C^* and the phase characteristic of update value secondary path filter C^* are approximate to each other when update value secondary path filter C^* and previous value secondary path filter C^* are in the same region on the complex plane. Accordingly, the active noise control device **10** of the present embodiment can simplify the determination of whether or not the phase characteristic of previous value secondary path filter C^* and

the phase characteristic of update value secondary path filter C^* are approximate to each other.

Other Embodiments

In the first embodiment, the active noise control device **10** includes the initial value table **56** and the update value table **58**, but need not necessarily include update value table **58**. In this case, the secondary path filter coefficient updating unit **40** determines whether or not the phase characteristic of the previous secondary path filter C^* and the phase characteristic of the secondary path filter C^* having the initial value as a coefficient are approximate to each other. The initial value is a value corresponding to the control target frequency f stored in the initial value table **56**. When it is determined that the phase characteristic of the previous secondary path filter C^* and the phase characteristic of the secondary path filter C^* having the initial value as a coefficient are approximate to each other, the secondary path filter coefficient updating unit **40** inputs the initial values of the initial value table **56** to the pre-update values of the update expressions and updates the filter coefficients $C0^*$ and $C1^*$. When it is determined that the phase characteristic of the previous secondary path filter C^* is not approximate to the phase characteristic of the secondary path filter C^* having the initial value as a coefficient, the secondary path filter coefficient updating unit **40** updates the filter coefficients $C0^*$ and $C1^*$ by inputting the updated filter coefficients $C0^*$ and $C1^*$ to the pre-update values of the update expressions. Every time the filter coefficients $C0^*$ and $C1^*$ are updated, the initial value table operating unit **62** rewrites the initial values of the initial value table **56** to the updated filter coefficients $C0^*$ and $C1^*$.

Technical Ideas Obtained from Embodiments

A description will be given below concerning technical concepts that are capable of being grasped from the above-described embodiments.

The active noise control device **(10)** performs active noise control for controlling the speaker **(16)**, based on an error signal that changes in accordance with a synthetic sound of noise transmitted from a vibration source and a canceling sound output from the speaker to cancel the noise, and includes the basic signal generating unit **(26)** configured to generate a basic signal corresponding to a control target frequency, the control signal generating unit **(28)** configured to perform signal processing on the basic signal by a control filter, which is an adaptive notch filter, to generate a control signal that controls the speaker, the estimated noise signal generating unit **(32)** configured to perform signal processing on the basic signal by a primary path filter, which is an adaptive notch filter, to generate an estimated noise signal, the first estimated cancellation signal generating unit **(30)** configured to perform signal processing on the control signal by a secondary path filter, which is an adaptive notch filter, to generate a first estimated cancellation signal, the first virtual error signal generating unit **(46)** configured to generate a first virtual error signal from the error signal, the first estimated cancellation signal, and the estimated noise signal, and the secondary path filter coefficient updating unit **(40)** configured to sequentially and adaptively update a coefficient of the secondary path filter based on the control signal and the first virtual error signal in a manner that a magnitude of the first virtual error signal is minimized, and the initial value table **(56)** configured to store an initial value of the coefficient of the secondary path filter in table form in

association with a frequency, wherein the secondary path filter coefficient updating unit is configured to determine, before updating the coefficient of the secondary path filter, whether or not a phase characteristic of the secondary path filter when the initial value corresponding to the frequency in the initial value table is the coefficient of the secondary path filter and a phase characteristic of the secondary path filter after previous coefficient updating in the secondary path filter coefficient updating unit, are approximate to each other, update, when the phase characteristics are determined to be approximate, the coefficient of the secondary path filter by using the initial value as a previous value, and update, when the phase characteristics are determined not to be approximate, the coefficient of the secondary path filter by using the coefficient of the secondary path filter after the previous coefficient updating as a previous value by the secondary path filter coefficient updating unit.

In the active noise control device, if a phase difference between the phase characteristic of the secondary path filter when the initial value corresponding to the frequency in the initial value table is the coefficient of the secondary path filter and the phase characteristic of the secondary path filter after the previous coefficient updating in the secondary path filter coefficient updating unit, is less than a predetermined angle, the secondary path filter coefficient updating unit may be configured to determine that the phase characteristic of the secondary path filter when the initial value corresponding to the frequency in the initial value table is the coefficient of the secondary path filter and the phase characteristic of the secondary path filter after the previous coefficient updating in the secondary path filter coefficient updating unit are approximate to each other.

In the active noise control device, if, when a complex plane is divided into a plurality of regions at predetermined angles, the phase characteristic of the secondary path filter when the initial value corresponding to the frequency in the initial value table is the coefficient of the secondary path filter and the phase characteristic of the secondary path filter after the previous coefficient updating in the secondary path filter coefficient updating unit are in the same region, it may be determined that the phase characteristic of the secondary path filter when the initial value corresponding to the frequency in the initial value table is the coefficient of the secondary path filter and the phase characteristic of the secondary path filter after the previous coefficient updating in the secondary path filter coefficient updating unit are approximate to each other.

The active noise control device may include the update value table (58) configured to store an update value of the coefficient of the secondary path filter in table form in association with the frequency, and the update value table operating unit (64) configured to write the initial value of the initial value table as the update value in the update value table when the active noise control is started, and write the coefficient of the secondary path filter updated by the secondary path filter coefficient updating unit as the update value in the update value table during the active noise control, wherein the secondary path filter coefficient updating unit may be configured to determine, before updating the coefficient of the secondary path filter, whether or not the phase characteristic of the secondary path filter when the update value corresponding to the frequency in the update value table is the coefficient of the secondary path filter and a phase characteristic of the secondary path filter after previous coefficient updating in the secondary path filter coefficient updating unit are approximate to each other, update, when the phase characteristics are determined to be

approximate, the coefficient of the secondary path filter by using the update value as a previous value, and update, when the phase characteristics are determined not to be approximate, the coefficient of the secondary path filter by using the coefficient of the secondary path filter after the previous coefficient updating as a previous value by the secondary path filter coefficient updating unit.

The active noise control device may include the initial value table operating unit (62) configured to rewrite the initial value of the initial value table with the update value of the update value table when the active noise control terminates.

The active noise control device may include the reference signal generating unit (34) configured to perform signal processing on the basic signal by the secondary path filter to generate a reference signal, the second estimated cancellation signal generating unit (36) configured to perform signal processing on the reference signal by the control filter to generate a second estimated cancellation signal, the second virtual error signal generating unit (52) configured to generate a second virtual error signal from the second estimated cancellation signal and the estimated noise signal, the control filter coefficient updating unit (42) configured to sequentially and adaptively update a coefficient of the control filter based on the reference signal and the second virtual error signal in a manner that a magnitude of the second virtual error signal is minimized, and the primary path filter coefficient updating unit (38) configured to sequentially and adaptively update a coefficient of the primary path filter based on the basic signal and the first virtual error signal in a manner that a magnitude of the first virtual error signal is minimized.

The present invention is not particularly limited to the embodiments described above, and various modifications are possible without departing from the essence and gist of the present invention.

What is claimed is:

1. An active noise control device that performs active noise control for controlling a speaker, based on an error signal that changes in accordance with a synthetic sound of noise transmitted from a vibration source and a canceling sound output from the speaker to cancel the noise, the active noise control device comprising one or more processors that execute computer-executable instructions stored in a memory, wherein the one or more processors execute the computer-executable instructions to cause the active noise control device to:

generate a basic signal corresponding to a control target frequency;

perform signal processing on the basic signal by a control filter, which is an adaptive notch filter, to generate a control signal that controls the speaker;

perform signal processing on the basic signal by a primary path filter, which is an adaptive notch filter, to generate an estimated noise signal;

perform signal processing on the control signal by a secondary path filter, which is an adaptive notch filter, to generate a first estimated cancellation signal;

generate a first virtual error signal from the error signal, the first estimated cancellation signal, and the estimated noise signal;

sequentially and adaptively update a coefficient of the secondary path filter based on the control signal and the first virtual error signal in a manner that a magnitude of the first virtual error signal is minimized;

19

store in an initial value table an initial value of the coefficient of the secondary path filter in table form in association with a frequency,

determine, before updating the coefficient of the secondary path filter, whether or not a phase characteristic of the secondary path filter when the initial value corresponding to the frequency in the initial value table is the coefficient of the secondary path filter and a phase characteristic of the secondary path filter after previous coefficient updating, are approximate to each other; update, when the phase characteristics are determined to be approximate, the coefficient of the secondary path filter by using the initial value as a previous value; and update, when the phase characteristics are determined not to be approximate, the coefficient of the secondary path filter by using the coefficient of the secondary path filter after the previous coefficient updating as a previous value.

2. The active noise control device according to claim 1, wherein if a phase difference between the phase characteristic of the secondary path filter when the initial value corresponding to the frequency in the initial value table is the coefficient of the secondary path filter and the phase characteristic of the secondary path filter after the previous coefficient updating, is less than a predetermined angle,

the one or more processors cause the active noise control device to determine that the phase characteristic of the secondary path filter when the initial value corresponding to the frequency in the initial value table is the coefficient of the secondary path filter and the phase characteristic of the secondary path filter after the previous coefficient updating are approximate to each other.

3. The active noise control device according to claim 1, wherein if, when a complex plane is divided into a plurality of regions at predetermined angles, the phase characteristic of the secondary path filter when the initial value corresponding to the frequency in the initial value table is the coefficient of the secondary path filter and the phase characteristic of the secondary path filter after the previous coefficient updating are in a same region,

the one or more processors cause the active noise control device to determine that the phase characteristic of the secondary path filter when the initial value corresponding to the frequency in the initial value table is the coefficient of the secondary path filter and the phase characteristic of the secondary path filter after the previous coefficient updating are approximate to each other.

20

4. The active noise control device according to claim 1, wherein the one or more processors cause the active noise control device to:

store in an update value table an update value of the coefficient of the secondary path filter in table form in association with the frequency; and

write the initial value of the initial value table as the update value in the update value table when the active noise control is started, and write the updated coefficient of the secondary path filter as the update value in the update value table during the active noise control, determine, before updating the coefficient of the secondary path filter, whether or not the phase characteristic of the secondary path filter when the update value corresponding to the frequency in the update value table is the coefficient of the secondary path filter and a phase characteristic of the secondary path filter after previous coefficient updating are approximate to each other; update, when the phase characteristics are determined to be approximate, the coefficient of the secondary path filter by using the update value as a previous value; and update, when the phase characteristics are determined not to be approximate, the coefficient of the secondary path filter by using the coefficient of the secondary path filter after the previous coefficient updating as a previous value.

5. The active noise control device according to claim 4, wherein the one or more processors cause the active noise control device to rewrite the initial value of the initial value table with the update value of the update value table when the active noise control terminates.

6. The active noise control device according to claim 1, wherein the one or more processors cause the active noise control device to:

perform signal processing on the basic signal by the secondary path filter to generate a reference signal; perform signal processing on the reference signal by the control filter to generate a second estimated cancellation signal;

generate a second virtual error signal from the second estimated cancellation signal and the estimated noise signal;

sequentially and adaptively update a coefficient of the control filter based on the reference signal and the second virtual error signal in a manner that a magnitude of the second virtual error signal is minimized; and sequentially and adaptively update a coefficient of the primary path filter based on the basic signal and the first virtual error signal in a manner that a magnitude of the first virtual error signal is minimized.
